his ATTORNEY

UNITED STATES PATENT OFFICE.

WILLIAM S. FISKE, OF STAMFORD, CONNECTICUT.

STEAM-BOILER.

SPECIFICATION forming part of Letters Patent No. 224,890, dated February 24, 1880.

Application filed December 15, 1879.

To all whom it may concern:

Be it known that I, WILLIAM S. FISKE, of Stamford, in the county of Fairfield and State of Connecticut, have invented a new and valuable Improvement in Steam-Boilers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a central vertical section of this invention. Fig. 2 is a vertical section showing the exterior water-connection. Fig. 3 is a sectional view of the connecting water-tubes between the boilers. Figs. 4 and 5 are horizontal sections.

This invention has relation to steam-boilers; and it consists in the construction and novel arrangement, in combination, of two separate but connected boilers, one acting principally as a generator of steam and the other acting chiefly as a holder of steam and water, the flues of the generating-boiler being placed far below the water-line, and strong tubular water-connections being placed between the two boilers.

It also consists in the construction and novel arrangement of the tubular water-connections, the nettings or perforated plates thereof, and the external safety-connection, all as herein-after shown and described.

In the accompanying drawings, the letter A designates the outer wall of the boiler or the wall of the boiler-case. B represents the fire-box, and C the lower or generating boiler, having through it the upright flame-flues a. D is an intermediate space extending horizontally between the two boilers, and E is the upper boiler, supported within the wall A, and having in it or around it a flue-space, b, for the passage of the heated products of combustion.

Usually the fire-box is built up within the lower boiler, so that its outer portion extends down around the said box, the case-wall A forming the outer wall of this boiler; but, if preferred, this lower boiler may be built entirely above the fire-box. Between the two boilers are arranged the water-connections c,

which are tubular in form and pass through the horizontal flue-space D.

The general water-line of the boiler is indicated by the dotted line y, and it will at once be apparent that in this arrangement the flame-flues a are far below this line. The connections c, which form the water communication between the two boilers, are designed to be larger in diameter than the flame-flues, and are preferably of the construction shown, in order to insure perfect joining. Holes d d of proper diameter are formed in the bottom head of the upper or holding boiler and in the top head of the lower or steam-generating boiler. Through the hole in the head of the upper boiler is passed a tubular section, e, having a shoulder, f, on which the head rests, and above and below this shoulder external threads, g and h, and a convex-beveled lower margin, k, which fits the concave-beveled upper edge, k', of the lower section, e', which is passed downward in the hole in the head of the lower boiler. This section e' is made with a marginal flange, l, below which is a shoulder, f', which rests on the head, and an external thread, g', is formed on that portion of the section which extends below the head to receive a screw-collar, m', having an inner wedging-lip, n', which is forced against the margin of the hole in the head from the under side and draws down the shoulder f' above, thereby forming a secure joint in this head.

In the head of the upper boiler a screw-collar, m, having an inner wedging-lip, n, engages the thread g of the section e, and being forced home forms a tight joint in a similar manner. The edges k and k' of the sections are drawn forcibly together by a coupling-collar, s, having a thread, h', to engage with the lower thread, h, of the upper section and an internal flange, l', to engage with the marginal flange l of the upper section.

In the connection is secured, by means of an inner ring, r, a diaphragm, p, of wire-netting or perforated metal. Upon the strength and security of these water-connections and their capacity for ready adjustment depends much of the usefulness of this boiler. The perforated diaphragm serves to prevent priming or foaming.

F represents the exterior pipe connecting the two boilers, running from the lower part of the upper one to the lower part of the lower one. This carries down from the upper boiler 5 any overflow from the lower or generating boiler, and thus serves as a safety-pipe.

This boiler is designed to be strong, durable, and safe, and it will be very effective, although economical in construction.

10 Having described this invention, what I claim, and desire to secure by Letters Patent, is—

15 1. The steam-boiler consisting of an upper steam and water holding boiler, E, heated by the products of combustion passing through the horizontal flue-space D and vertical flue-spaces, tubular water-connections *c*, below the water-line, and passing through the horizontal flue-space D, the perforated diaphragms in 20 said connections, and the steam-generating boiler C, below the water-connections, and separated from the upper boiler, E, by the flue-space D, all constructed and arranged to operate as shown and described.

2. The steam-boiler consisting of the upper 25 and lower separate boilers, E and C, separated by a horizontal flue-space, D, and connected by the adjustable tubular water-connections *c*, passing through said flue-space, and the exterior water-connection, F, acting as a safety- 30 pipe, substantially as specified.

3. The combination, with the upper boiler, E, and the lower boiler, C, below the water-line, and separated from the upper boiler by an intermediate horizontal flue-space, of the 35 shouldered and threaded tube-sections *e e'*, the screw - collars *m m'*, and the threaded and flanged coupling-collars, substantially as specified.

In testimony that I claim the above I have 40 hereunto subscribed my name in the presence of two witnesses.

WILLIAM SHERWOOD FISKE.
